UNITED STATES PATENT OFFICE.

ARTHUR W. WEEDEN, OF QUINCY, MASSACHUSETTS, ASSIGNEE, BY MESNE ASSIGNMENTS, TO WEEDEN, JOHNSON & CO., INC., A CORPORATION OF MASSACHUSETTS.

BATTING DEVICE FOR BASEBALL GAME APPARATUS.

1,416,918.

Specification of Letters Patent. Patented May 23, 1922.

Application filed March 12, 1921. Serial No. 451,814.

To all whom it may concern:

Be it known that I, ARTHUR W. WEEDEN, a citizen of the United States, residing at Quincy, in the county of Norfolk and State 5 of Massachusetts, have invented certain new and useful Improvements in Batting Devices for Baseball Game Apparatus, of which the following is a specification.

This invention relates to new and useful 10 improvements in game apparatus, and it is particularly applicable to base-ball game apparatus.

As at present constructed, apparatus of 15 this type is provided with a board that is marked out to simulate a base-ball playing field, having a diamond, home-plate, bases, pitcher's box, etc., such for instance as that shown by U. S. Patent #977,149, granted to me on November 29, 1910. At the home- 20 plate is positioned a device for the purpose of batting balls delivered from the pitcher's box. My present application relates to improvements that have been made to eliminate the objectionable features present in 25 the forms of batting devices heretofore in use.

In order that other persons skilled in the art to which my invention appertains, may construct and use my apparatus, I will now 30 describe in detail the salient features of my improvement.

In the following detailed description, which is illustrated by the accompanying drawings, and pointed out in the appended 35 claims, I have shown the preferred embodiment of my invention.

In the drawings:—

Figure 1, is a side elevation of the improved batting device, showing the parts 40 set and ready to "bat the ball";

Fig. 2, is a section taken on the line 2—2, of Fig. 1;

Fig. 3, is a plan view of Fig. 1;

Fig. 4, is a longitudinal section taken on 45 the line 4—4 of Fig. 3, with the parts in their rearmost position when engaged by a ball;

Fig. 5, is a view similar to Fig. 4, illustrating the parts in their outermost position, 50 and

Figs. 6, 7, and 8, are detail views.

Referring to the drawings, the device is composed of three pieces that are assembled one within the other, and tension means in

the form of a spring having limbs connecting two of the pieces. There is a base 10, having a pivot pin 11 extending downwardly from its bottom into an opening 12 of a board 13.

The board 13 is of the desired size and 60 contour to represent a playing field for baseball and I have in this application shown only a small portion thereof. Preferably said board is marked off substantially in the manner described in my said patent. 65

The base 10 of the device is preferably 70 formed from sheet metal, and it is provided with vertical side walls 14 (see Fig. 8) irregular in outline. The front ends of the side walls 14 of the base 10 have formed 75 therein V-shaped notches 15, while intermediate the length of the side walls are rectangular locking plate engaging notches 16. Between the two series of notches the height of the side walls is reduced somewhat, as shown.

A projector 17 is slidably mounted within 80 the base 10. This projector is formed with a bottom in which there is a slot 18 through which extends the pivot pin 11 of the base 10. The projector has side walls 19 rising 85 from its bottom, and its forward end is bent upwardly to provide a plate 20 against which the balls used in connection with the device are designed to contact. The plate 85

20 is somewhat wider than the width of the other portions of the device, and its extremities are bent rearwardly as shown. The front edges of the side walls 19 of the projector 17 are formed with V-shaped notches 90 21, while near the rear ends of the side walls are the openings 22 whose lower edges, upwardly inclining towards the forward end of the projector, as shown, function as a wedge at the proper times in the manner 95 hereinafter set forth.

Positioned within the projector 17 is a 100 rectangular plate 23, having lateral projections 24 extending from its sides at its forward end and lateral projections 25 extending from its sides at its rear end. The projections 24 of the plate 23 lie within the V-shaped notches 15 and 21 formed respectively in the side walls of the base piece 10 and the projector 17, while the projections 105 25 of the plate 23 extend through the openings 22 in the side walls of the projector 17.

Pivotedly mounted in the side walls of

the base 10 to the rear of rectangular notches 16, is a U-shaped bail 26. The free limbs of the bail are secured to the sides of the base 10 and its cross-piece is encircled by the coil of a spring 27. The spring 27 has relatively long free ends, one of which forms a link 28 that is pivotally connected to the front end of the plate 23, while the other is formed into a presser 29. The length of the limbs of the bail 26, and the length of the link 28 of the spring 27 is such that the coil of the spring lies over the forward end of the device, while the presser lies over its center, as shown in Fig. 1.

15 In the operation of the device, when it is desired to set the parts for the purpose of batting a ball, the projector 17 is slid outward slightly and the projections 25 of the plate 23 are inserted into the notches 16 of the base 10. By means of the presser 29, the spring is put under tension, and this causes the link 28 thereof to be flexed outwardly. In Figures 1 and 3, of the drawings, I have shown the device with parts thereof set.

20 When a ball used in playing the game hits the plate 20 of projector 17, its impact produces a backward movement of the projector relative to the base 10, and drives it into the position shown in Fig. 4; the accompanying movement of the inclined edges of the openings 22 meanwhile serving to wedge upwardly the rear projections 25 of the locking plate 23 until the dislodgement of the same from the lock-engaging notches 16 in the sides of the base 10 is effected. Therefore the plate 23, which has previously been locked in position, is released, and through the link 28 of the spring 27, it is propelled forwardly.

25 40 During the forward movement of the plate 23, its projections 25 engage the front of the openings 22 of the projector 17, and in this manner the projector is carried forwardly. Thus it will be seen that when the ball hits the end plate 20 of the projector 17, it first drives the end plate rearwardly, this movement releasing the locking means, and then it is repelled outwardly being batted out upon the playing field of the base-ball game apparatus.

50 The base 10 of the device through the pin 11 thereof can be swung to any angular position, therefore, when the game is being played the balls can be batted to any desired part of the field by placing the device in the desired position. Likewise, the balls can be batted either fast or slow according to the amount of tension exerted upon the presser 29 of the spring, or according to the force with which they are thrown against the projector.

55 It is to be noted that the device can be economically constructed, and it is designed to withstand hard usage without becoming defective. It is to be understood that I can,

if so desired, modify the form and proportion of the parts without departing from the spirit of the appended claims.

60 The proper depth of the V-shaped notches 15 in the front edges of the sides of the base 10 is of importance in contributing to a satisfactory working of my invention. This depth should be such that when the lateral projections 24 at the front of the locking plate 23 come to rest within the apex of such notches, they serve to align said plate in parallelism with the side walls 19 of the projector 17, thus obviating any contact or binding between the said walls and the lateral edges of said plate which would interfere with the free dropping of the projections 25 at the rear end of said plate within the notches 16 when the projector is being set for batting action.

65 Having thus described my invention, what I claim is:—

1. A batting device for baseball games, and the like, comprising, a base having sides provided with lock-engaging notches, a projector slidably mounted in said base, said projector having its forward end adapted to receive the impact of the ball member to be batted, and having sides provided with openings having inclined wedge edges, a locking plate movable with the projector and provided with lock-engaging projections extending laterally therefrom through said wedge edged openings in the projector sides and adapted, in the rearward position of the projector relative to the base, to engage within the lock-engaging notches of the base, the wedge edges of said openings in the sides of the projector being adapted, in the rearward motion of the projector relative to the base due to impact of ball member on said projector, to release the lock-engaging projections of the locking plate from the lock-engaging notches of the base, and tension means interconnecting the locking plate and the base.

70 110 2. A batting device for baseball games, and the like, comprising a base having sides provided with lock-engaging notches, a projector slidably mounted in said base, said projector having at its forward end means for receiving the impact of the ball member to be batted, and having sides provided with openings having inclined wedge edges, a locking plate mounted in said projector, said plate being provided with lock-engaging 115 projections extending laterally therefrom through said wedge edged openings in the sides of the projector and adapted through the engagement of said ends within said openings, to communicate the movement 120 of the locking plate to the projector, said projections being adapted, in the rearward position of the projector relative to the base, to engage within the lock-engaging notches of the base, and to be raised therefrom by 125 130

the wedge edges of the openings in the sides of the projector as said projector is caused to move rearwardly relatively to the base in consequence of the impact of the ball element, and tension means interconnecting the locking plate and the base.

3. A batting device of the class described comprising, a base having sides provided with notches in their front edges and lock-
10 engaging notches intermediate the length of said sides, said base having a pivot pin ex-
tending therethrough and projecting downward into a game board and upward above its upper surface, a projector slidably
15 mounted in said base and having sides pro-
vided with V-shaped notches in their front edges and wedge edged openings near their rear ends and having an impact plate car-
ried on the front end thereof, said projector
20 having its bottom provided with a slot en-
gaging the pin of the base, a locking plate mounted in the projector and having lateral pro-
jections extending from its front and rear ends, the front projections passing
25 through the notches in the forward edges of the base and the projector, and the rear pro-
jections passing through the wedge edged open-
ings in the sides of the projector and adapted to be engaged in the lock-engaging
30 notches in the sides of the base when the device is set in operative position, said wedge edged openings in said projector sides having inclined edges whereby, when said projector is caused to move rearwardly relative
35 to the base in consequence of the impact thereon of a ball element, said rear pro-
jections of said locking plate are dislodged from said lock-engaging notches in the sides of the base, and tension means interconnecting
40 the locking plate and the base.

4. In a device of the class described, a base having sides provided with notches in their front edges and lock engaging notches intermediate thereof, said base having a pivot pin extending therethrough and pro-
45 jecting downward into a game board and up-
ward above its upper surface, a projector slidably mounted in said base and having

sides provided with notches in their front edges and openings near their rear ends and 50 a vertical plate on its forward end, said projector having its bottom, provided with a slot engaging the pin of the base, a locking plate mounted in the projector and having lateral projections extending from its front 55 and rear ends, the front projections passing through the notches in the sides of the base and projector and the rear projections passing through the openings in the sides of the projector and adapted to be engaged in the 60 intermediate notches in the sides of the base when the device is set in operative position, and tension means connecting the front end of the locking plate and the sides of the base, said tension means being adapted to 65 force the locking plate forwardly when the projector is driven rearwardly to release the projections of the locking plate from engage-
ment with the side notches of the base.

5. In a device of the class described hav- 70 ing a base provided with sides and a pro-
jector slidably mounted within said base and having sides, and a locking plate having rear projections adapted, in the operative 75 locking position of the plate to drop and en-
gage within notches provided in part in the sides of the base and in part in the sides of the projector, which notches are arranged to register in position and to be engaged by said rear projections of the locking plate in 80 the locked position of said base and said pro-
jector, notches provided in the front edges of the sides of said base which are arranged to receive front projections carried by said locking plate, and thereby to align said lock- 85 ing plate with respect to said projector, so as to prevent any binding thereof with said projector which would have the effect of pre-
venting the rear projections of said locking plate from freely dropping into their lock- 90 ing position when the registering position of the notches provided in base and in the projector is reached.

In testimony whereof I have affixed my signature.

ARTHUR W. WEEDEN.
